The figure on the drawing is a face view of a font of letters and numerals showing my new design.

The dominant features of my design reside in the letters A, B, K, L, M, N, R, V, W, X, and Y and the numerals 2, 3, 4, 6, 7, 8, and 9, which have been shaped and tapered as shown.

I claim:

The ornamental design for a font of letters and numerals, as shown and described.
